Specification for Design.

Patented June 7, 1921.

Application filed March 15, 1920. Serial No. 366,122. Term of patent 14 years.

To all whom it may concern:

Be it known that I, ALFRED A. GLIDDEN, of Watertown, Massachusetts, have invented a new, original, and ornamental Design for Non-Skid Treads for Automobile-Tires, of which the following is a specification, reference being had to the accompanying drawing, forming a part thereof.

The figure is a plan view of a section of the tread showing my new design.

I claim:

The ornamental design for a non-skid tread for automobile tires as shown.

ALFRED A. GLIDDEN.
